SAFETY MILK BOTTLE CONTAINER

William Harold Van Buskirk, Vancouver, British Columbia, Canada

Application December 2, 1935, Serial No. 52,583

2 Claims. (Cl. 232—42)

My present invention relates to certain new and useful improvements in devices for holding milk bottles against theft of the same and for holding them in a manner to protect the mouth of the bottle in a sanitary way.

More specifically, the invention has for an object to provide a very simple and inexpensive holder for attachment to the side of a door frame in cooperative relation to the door, the device 10 folding down when not in use to a compact structure that will not interfere with the opening and/or closing of the door.

Again, it is an object to provide a holder whose lock is pick-proof and requires an especially constructed "key" to unlock it.

Other objects will in part be obvious and in part be pointed out hereinafter.

To the attainment of the aforesaid objects and ends the invention still further resides in the 20 novel details of construction, combination and arrangement of parts, all of which will be first fully described in the following detailed description, and then be particularly pointed out in the appended claims, reference being had to the 25 accompanying drawings, in which:—

Figure 1 is a perspective view of a doorway with my invention in place, but not in use.

Figure 2 is an enlarged detail perspective view of the device in use, locked.

Figure 3 is an inverted perspective view of the device, positioned for insertion or removal of a bottle.

Figure 4 is a vertical section on the line 4—4 of Figure 2.

Figure 5 is a vertical section on the line 5—5 of Figure 4.

Figure 6 is an enlarged detail longitudinal section of the lock.

Figure 7 is a detail elevation and part section 40 of the "key".

In the drawings in which like numerals of reference indicate like parts in all the figures, 1 represents the door frame on the side face 1a of which is mounted the bottle holding device. 45 This device comprises a vertical plate 2, having a bottom flange 3, and at the top the plate 2 has hinged to it, as at 2x, the portion 6 of an L-shaped plate, the long portion 6a of which extends at right angles to the short portion 6 and parallels 50 the flange 3 when the plate portion 6 is in alignment with the plate 2. The plate 2 is held in place by means of screws 5 and diagonal key-hole slots 4.

The section 6 of the L-shaped plate has a 55 curved keeper 9, welded or otherwise secured to

it, the keeper having a bolt hole 8 for the reception of the locking end 16 of the latch bolt 23, hereinafter again referred to.

Pivoted to the plate portion 6a, at 10, is a channeled member 11 having vertical sides 12 with under-turned edges 13 to hold a milk bottle by the neck ring. The front end of the channeled member 11 is permanently closed, as at 14, while the rear end is open. Extending across the member 11 from one side 12 is the casing 15 which carries the latch bolt 23 hereinbefore referred to. The casing 15 is welded or otherwise secured to the sides 12. It projects through one side and at the projecting end has stops 18 against which the collar 17, on the bolt 23, rests 15 when the bolt has its latching end 16 projected by the spring 21 that lies within the casing 15 between the collar 17 and the inward projections 25 stamped or otherwise formed in the casing 15. Within the casing 15 and at the front end of the 20 same there is a ring 24 which is held against the adjacent side 12 of the channeled member by means of a spring 22. The bolt 23 has a neck 19 and a tapered head 20 within the confines of the spring 22. The side wall 12 adjacent that end 25 of the casing 15 which contains the ring 24 is provided with an aperture 26 of slightly less diameter than that of the casing 15 so as to serve as a stop for the ring 24. The hole 26, however, is slightly larger than the hole through the 30 ring 24.

The "key", by means of which the latch bolt 23 may be withdrawn from its locking position, is best shown in Figure 7, by reference to which it will be observed that the "key" comprises a 35 sleeve 27 having a finger-engaging head 28 in which sleeve and head a rod 29 is longitudinally slid able. The rod 29 has a split end of tubular form comprising springy tongs 30. The rod 29 at its other end has a head 31 and carries a 40 spring 32 between the heads 28 and 31 for drawing the tongs 30 into the sleeve 27 when the "key" parts are in a normal position.

Assume the channeled member 11 to be locked and it is desired to release it so that it may be 45 swung on the pivot 10 for the insertion of the milk bottle. The milkman inserts the "key" through the hole 26. In doing this the sleeve 27 will force the ring 24 back and by pulling the heads 28 and 31 together against the tension of 50 the spring 32 the tongs will be split to grip the head 20 of the latch bolt 23. Upon releasing the head 28 the spring 32 will force the sleeve 27 toward the tongs 30 and cause them to grip the head 20. The operator then pulls the head 31 55

and in doing so retracts the bolt 23 from the keeper aperture 8 and thus frees the channeled member 11 to swing about the pivot 10.

33 represents a cash box which is slidably held 5 in the channeled member 11 and retained against unauthorized removal when the channeled member is in the locked position.

It will be observed that when the channeled member 11 is in the locked position its open end 10 will be against the door 34 which serves to close the open end of the channeled member 11. For the housewife to remove the milk bottle and cash box from the holder it is only necessary to open the door 34 which will swing it away from the 15 holder and permit the bottle 35 to be withdrawn.

From the foregoing description, taken in connection with the accompanying drawings, it is thought that the construction, operation and advantages of my invention will be clear to those 20 skilled in the art.

What I claim is:

1. In a milk bottle holder wherein a bottle suspending member is pivotally mounted on a supporting member, means to lock said suspending member against turning which means comprises a spring pressed locking bolt on the suspending member, the axis of which bolt lies in a plane 25 normal to the pivotal axis of said suspending

member, and a wedge-like body carried by the supporting member and having a bolt hole adjacent its larger end, said body being positioned to be engaged by said bolt as said suspending member is turned in one direction to retract the bolt 5 and then permit it to enter said bolt hole for purposes described.

2. In a milk bottle holder, a supporting member comprising a flat plate having provisions for mounting it on a door frame and an L-plate 10 hinged to said flat plate along the edge of the shorter portion of the L-plate whereby when said L-plate is raised the shorter portion thereof will lie in the plane of said flat plate and the longer portion will lie at right angles thereto, a wedge-shaped body rigidly secured to the shorter portion of said L-plate and having a bolt hole adjacent its larger end, a bottle suspending member 15 pivotally mounted on the larger portion of said L-plate to turn on an axis normal thereto, and a spring pressed locking bolt carried by said suspending member to engage said wedge-shaped body for purposes described, the depth of said suspending member being not more than the 20 depth of said shorter portion whereby when said L-plate is folded down it will lie with its larger portion paralleling said flat plate.

WILLIAM HAROLD VAN BUSKIRK.
